FIG 3

UNITED STATES PATENT OFFICE.

WILLIAM E. GREENAWALT, OF DENVER, COLORADO.

ELECTROLYTIC DIAPHRAGM.

1,387,705.

Specification of Letters Patent. Patented Aug. 16, 1921.

Application filed May 25, 1920. Serial No. 384,143.

To all whom it may concern:

Be it known that I, WILLIAM E. GREENAWALT, a citizen of the United States, residing in the city and county of Denver and 5 State of Colorado, have invented certain new and useful Improvements in Electrolytic Diaphragms, of which the following is a specification.

The invention represents a portion of the 10 apparatus disclosed in my co-pending process application, Serial No. 66,621, filed December 13, 1915, and has for its object the effective construction of large size diaphragms, which are unaffected either by the electric 15 current or by the electrolyte.

Diaphragms made of porous slabs have been in use for a long time. The size of the diaphragms were usually limited to the size of the individual slabs, or sections. I over- 20 come the difficulty by using metal rods, incased in a suitable insulating material, to hold the porous slabs in place. The rods are anchored to the sides of the tank.

In the accompanying drawings Figure 1 25 shows a cross section of an electrolytic cell with the diaphragms in place; Fig. 2, a longitudinal section, and Fig. 3, a detail cross section of the invention.

In the drawings, 1 is an electrolytic tank, 30 2 the porous diaphragm slabs, or sections, 3 the anode, 4 the cathodes, 5 a metal rod, fitted into the grooved joints 6 of the porous slabs, 7 the insulating covering of the rod, and 8 a fibrous material to make a fairly 35 tight joint between the porous slabs and the insulating covering of the metal rod. This same fibrous material may also be used in the joints in which there is no stiffening rod.

The porous slabs will ordinarily be made 40 of burnt porous clay, or sand with an adhesive binder, and are preferably fashioned with a groove in the horizontal joints. The rod is preferably made of steel, and is preferably incased in a hard rubber tubing. 45 Asbestos wicking is a good fibrous material for the joints. The rods and diaphragms are anchored in position by the side strips 9, which are fastened to the sides of the tank.

It is desirable to cement the rod in the rubber tubing. The steel rod gives the desired 50 strength to the built-up diaphragm, while the rubber tubing, which protects it, is unaffected either by the electric current or by the electrolyte.

55 The slabs forming the diaphragm may be

made of silica sand mixed with an adhesive binder and subjecting the mixture in the form desired to a high temperature to cause semifusion. Or a mixture of good clay and saw dust may be compressed to the form desired and the dried form may then be subjected to a sufficient temperature to bake the clay and burn out the saw dust. 60

I claim:

1. An electrolytic diaphragm composed 65 of a plurality of porous sections having grooved edges and metal rods inclosed in rubber tubing inserted in the grooves between the porous sections to support them.

2. An electrolytic diaphragm composed of 70 porous plates, and means for holding the plates together consisting of metal rods inclosed in a material unaffected by the electric current and by the electrolyte, and means for supporting the rods and plates 75 attached to the sides of the electrolytic tank.

3. In electrolytic apparatus a diaphragm built up of porous sections, metal rods in the joints of the sections to support and stiffen 80 the diaphragm, and a protecting medium surrounding the rods which is unaffected either by the electric current or by the electrolyte.

4. In electrolytic apparatus a diaphragm 85 built up of porous sections, metal rods in the joints of the sections to support and stiffen the diaphragm, a protecting medium surrounding the rods which is unaffected by the electric current or by the electrolyte, and a 90 fibrous material interposed between the porous sections and protecting medium to make a tight joint.

5. In electrolytic apparatus, a diaphragm built up of porous sections, metal rods in the 95 joints of the sections to support and stiffen the diaphragm, a protecting medium surrounding the rods which is unaffected by the electric current or the electrolyte, and a pliable material which is unaffected by the electric current or by the electrolyte interposed 100 between the porous sections and the protecting medium.

6. In electrolytic apparatus a diaphragm built up of porous sections, rods in the joints 105 of the sections to support and stiffen the diaphragm, and a protecting medium surrounding the rods which is substantially unaffected by the electric current or by the electrolyte.

WILLIAM E. GREENAWALT.
